DOOR PUSH BAR

Paul Junior Schwind, South Bend, Ind., assignor to Kawneer Company, Niles, Mich., a corporation of Delaware

Filed Oct. 17, 1960, Ser. No. 62,515

Term of patent 14 years

(Cl. D10—8)

FIG. 1 is a front perspective view of a door push bar embodying the new design;

FIG. 2 is an end elevational view of the door push bar of FIG. 1; and

FIG. 3 is a front elevational view of the door push bar of FIG. 1.

I claim:

The ornamental design for a door push bar, substantially as shown.
